(57) **CLAIM**

The ornamental design for a reflex plate, as shown.

DESCRIPTION

FIG. 1 is a front elevational view of a reflex plate of my new design;

FIG. 2 is a rear elevational view of the reflex plate;

FIG. 3 is a top plan view of the reflex plate;

FIG. 4 is a bottom plan view of the reflex plate;

FIG. 5 is a left side elevational view of the reflex plate;

FIG. 6 is a right side elevational view of the reflex plate; and,

FIG. 7 is a perspective view of the reflex plate.
